SWITCH FOR STARTER SYSTEMS

Frank J. Kirnberger, Milwaukee, Wis.

Application February 20, 1941, Serial No. 379,878

1 Claim. (Cl. 200—15)

This invention relates to internal combustion engines and more particularly the electric starting systems thereof.

The primary object of this invention resides in the provision of an electric starting system for internal combustion engines, particularly those used in automobiles, adapted to start the same prior to starting in low and freezing temperatures.

Another object of this invention resides in the provision of an electric starting system for automobiles consisting of a dual source of electricity, the units of which are adapted to be selectively connected to the starter of the engine.

A further object of this invention resides in the provision of an electric starting system for automobiles consisting of a dual source of electricity the units of which are adapted to be electrically connected to the starter of the engine either singularly or in conjunction with one another.

A still further object of this invention resides in the provision of an electric starting system for automobiles consisting of a dual source of electricity, the circuits of which are adapted to be controlled by means whereby either or both of the electric sources of supply may be connected to the starter of the engine.

Aside from the aforesaid objects this invention resides in the particular construction of the switch.

Among the many objects of this invention is the particular construction and arrangement of the stationary contact blades of the switch relative to the movable blades thereof.

With these and other objects in view this invention relates to certain novel features of construction and arrangement of elements to be hereinafter set forth in the specification, illustrated in the accompanying drawing and pointed out in the appended claim and, while this disclosure depicts my present conception of the invention, the right is reserved to resort to such changes in construction and arrangement of elements as come within the scope of the claim.

In the accompanying drawing forming a part of this application:

Fig. 1 is a diagrammatic view of the electric starting system of an internal combustion engine as constructed in accordance with this invention.

Fig. 2 is a front view of the switch showing the movable contact blades in open position.

Fig. 3 is a side view thereof showing the mov-

able contact blades open in full lines and closed in their several positions by dotted lines.

Fig. 4 is a detail perspective view of a portion of the base of the switch with the stationary blades supported thereby.

In the present embodiment of this invention the letter M designates an internal combustion engine, preferably mounted in an automobile, and having the usual electric starter S. The starter 10 S is electrically connected to pivoted blades 5 of a switch 6 by a conduit 7, adapted to be electrically connected to batteries A and B through the instrumentality of conduits 8, 9, 10 and 11 with the terminals of conduits 8 and 9 disposed for dual contact with the pivoted blades 5 while the terminals of conduits 10 and 11 are disposed for selective connection thereto by the pivoted blades.

With the switch 6 so disposed relative to the 20 contacts of the aforesaid conduits 8 and 9, electric energy is transmitted from batteries A and B to the starter S so as to start the engine M under a heavy load caused by the lubricant therein becoming congealed during freezing temperatures while starting under normal or high temperatures is caused by manipulating the pivoted blades alternately into engagement with either of the terminals or conduits 10 and 11.

The blades 5 are pivotally secured to a substantially U-shape bracket 12 mounted on a dielectric base 13 as by a terminal bolt 14 bearing against a substantially V-shape boss 15 formed on the base, said bolt 14 being utilized to electrically connect the conduit 7 to the blades 5.

Secured as by terminal bolts 16 to the dielectric base are stationary contact blades 17 and 18 each comprising parallel members 19 and 20 disposed in close relation as indicated at 21 with certain areas thereof widely separated as 40 at 22 to form dead areas spaced out of horizontal alignment beyond the base so as to permit alternate engagement of the pivotal blades 5 with the stationary blades when connecting either of conduits 10 and 11 to conduit 7.

The free ends of stationary blades 17 and 18 are directed laterally as indicated at 23 to permit the pivotal blades 5 to readily enter between the members thereof.

In order to establish rigidity between the stationary blades and base they are secured thereto against the base of the boss by the terminal bolts 16.

Connecting the free ends of the pivotal blades 5 is a dielectric handle 24 of any approved type.

With this invention fully set forth it is mani-

fest that means are provided whereby the engine of automobiles can be readily started in either low or high temperatures and, through the simplicity of the embodiment thereof, the same can be cheaply manufactured and installed in the conventional starting systems of internal combustion engines with the minimum degree of labor.

Having thus described my invention what I claim and desire to protect by Letters Patent is:

An electric switch comprising a dielectric base, a substantially V-shape boss formed on the face of the base with its apex and base forming shoulders disposed inwardly of the adjacent edges of the base, a substantially U-shape terminal bracket seated on the base and resting against the shoulder at the apex of the boss, a terminal bolt securing the U-shaped bracket on the base, substantially L-shape stationary con-

tacts formed of pairs of elongated resilient members having offset areas unequal distances from the base seated on the base with their inner bent ends resting against the shoulders at the base of the boss, terminal bolts securing the stationary contacts on the base, contact blades pivotally secured to the U-shape bracket for initial entrance between companion members of each stationary contact simultaneously and alternately lodge between the offset areas in disconnected electrical relation therewith when swung toward the base, a dielectric handle connecting the pivoted blades, an electric conduit connected to the terminal bolt of the U-shape bracket and an electric conduit from different sources of electric supply connected to each terminal bolt of the stationary brackets.

FRANK J. KIRNBERGER.
